Primary Examiner — Catherine S Posthauer(74) *Attorney, Agent, or Firm* — Thompson Coburn LLP(57) **CLAIM**

The ornamental design for a handle for tote as shown and described.

DESCRIPTION

FIG. 1 is a top and front perspective view of a handle for a tote;

FIG. 2 is a top and rear perspective view thereof;

FIG. 3 is a top plan view thereof;

FIG. 4 is a bottom plan view thereof;

FIG. 5 is a front elevational view thereof;

FIG. 6 is a rear elevational view thereof; and,

FIG. 7 is a right-side elevational view thereof.

A left-side elevational view is not shown because it is a mirror image of the right-side elevational view shown in FIG. 7. The broken lines in the drawings form no part of the claimed design.
